[57] CLAIM

The ornamental design for an antenna balun, substantially as shown and described.

DESCRIPTION

FIG. 1 is a side elevational view of my new design for an antenna balun;

FIG. 2 is an end elevational view taken from the right or lefthand side of FIG. 1;

FIG. 3 is a top plan view thereof;

FIG. 4 is a bottom plan view thereof.

The non illustrated side of the antenna balun is the same as the illustrated side of FIG. 1.

FIG. 1

FIG. 2

FIG. 3

FIG. 4
